US0D1069528S

(12) **United States Design Patent** (10) **Patent No.:** **US D1,069,528 S**
(45) **Date of Patent:** **** Apr. 8, 2025**

(54) **LIFT PAD CENTERING TOOL**

(71) Applicant: **Gabriel Del Valle**, Chicago, IL (US)

(72) Inventor: **Gabriel Del Valle**, Chicago, IL (US)

(**) Term: **15 Years**

(21) Appl. No.: **29/856,416**

(22) Filed: **Oct. 13, 2022**

(51) **LOC (15) Cl.** **12-05**

(52) **U.S. Cl.**

USPC **D34/31**

(58) **Field of Classification Search**

USPC D8/14, 349, 354, 356; D34/28, 31
CPC B66F 7/00; B66F 7/04; B66F 7/16; B66F
7/20; B66F 7/28

(57) **CLAIM**

The ornamental design for a lift pad centering tool as shown and described.

DESCRIPTION

FIG. 1 is a perspective view of the lift pad centering tool showing the new design;

FIG. 2 is a right-side view of the lift pad centering tool showing the new design;

FIG. 3 is a left-side view of the lift pad centering tool showing the new design;

FIG. 4 is a front elevation of the lift pad centering tool showing the new design;

FIG. 5 is a rear elevation of the lift pad centering tool showing the new design;

FIG. 6 is top plan view of the lift pad centering tool showing the new design; and,

FIG. 7 is a bottom view of the lift pad centering tool showing the new design.

The broken lines illustrate a socket and button for controlling a sight beam that form no part of the claimed design.

1 Claim, 6 Drawing Sheets
